DARNING ATTACHMENT FOR SEWING MACHINES

Werner W. Schwartz, Jackson Heights, N. Y., assignor to Consolidated Sewing Machine Corp.,
New York, N. Y., a corporation of New York

Application January 19, 1953, Serial No. 23,176

Term of patent 3½ years

(Cl. D70—2)

To all whom it may concern:

Be it known that I, Werner W. Schwartz, a citizen of the United States, residing at Jackson Heights, in the county of Queens and State of New York, have invented a new, original, and ornamental Design for a Darning Attachment for Sewing Machines, of which the following is a specification, reference being had to the accompanying drawing, forming part thereof.

Figs. 1 and 2 are front and side views, and Fig.

3 is a top plan view of a darning attachment for sewing machines embodying my new design.

I claim:

The ornamental design for a darning attachment for sewing machines, substantially as shown.
